CLAIM

The ornamental design for combined advertising sign and tee marker for golf course teeing areas, as shown and described.

DESCRIPTION

FIG. 1 is a front perspective view of a combined advertising sign and tee marker for course teeing areas showing my new design;
FIG. 2 is a left side elevational view thereof, with the opposite side being a mirror image;
FIG. 3 is a rear elevational view thereof;
FIG. 4 is a front perspective view of a second embodiment thereof;
FIG. 5 is a left side elevational view thereof, with the opposite side being a mirror image;
FIG. 6 is a rear elevational view thereof;
FIG. 7 is a perspective view from one side and above showing the ornamental appearance of a third form of sign in accordance with this invention;
FIG. 8 is a side elevation view of the sign of FIG. 7; and,
FIG. 9 is a rear elevation view of the sign of FIG. 7 showing the side hidden in FIG. 7.

FIG. 1

FIG. 2

FIG. 3

FIG. 4

FIG. 5

FIG. 6

FIG. 7

FIG. 8

FIG. 9
